UNITED STATES PATENT OFFICE.

WILLIAM R. MILLER, OF PITTSBURG, PENNSYLVANIA, ASSIGNOR TO THE FORTER-MILLER ENGINEERING COMPANY, OF PITTSBURG, PENNSYLVANIA, A CORPORATION OF PENNSYLVANIA.

REVERSE-VALVE.

No. 833,170.

Specification of Letters Patent.

Patented Oct. 16, 1906.

Application filed December 12, 1905. Serial No. 291,406.

To all whom it may concern:

Be it known that I, WILLIAM R. MILLER, a citizen of the United States, residing at Pittsburg, in the county of Allegheny and State of Pennsylvania, have invented or discovered new and useful Improvements in Reverse-Valves, of which the following is a specification.

My invention relates to reverse-valves with water seals, and has for its object to prevent the waste of gas during the time the valve is moving from one position to another.

In water-sealed valves in use with gas-producers and regenerative or other furnaces the gas from the producer is permitted to go directly to the chimney during the time the water seal is broken by the shifting of the valve from one position to another.

It is the object of the present invention to prevent this waste of gas by preventing the travel of the gas from the time the valve rises out of the water till it is again in the water.

Among the many ways by which the flow of gas may be interrupted during the reversal of the gases I have chosen for illustration the one shown on the accompanying drawings, on which—

Figure 1 is a side elevation of my invention with a portion broken away; Fig. 2, a horizontal section on the line II II of Fig. 1; Fig. 3, a vertical section on the line III III of Fig. 1; Fig. 4, an end elevation, and Fig. 5 a fragmentary view, showing in side elevation how the carriage is secured to the piston-rod of the carriage-moving piston.

On the drawings, 1 represents the valve-casing, having its lower edge supported in the water-pan 2 below the water-line. This casing is wholly open on its lower side, but is entirely inclosed gas-tight elsewhere. At its top is the gas-inlet 3, provided with the valve 4. Through this inlet the gas from the producer enters the valve-casing.

The bottom of the water-pan 2 has three gas-ports, the central one, 5, leading to the chimney or stack and the end ones, 6 and 7, leading to the usual furnace or other device for which the valve is adapted. The ports 5, 6, and 7 are formed by flanges which rise above the water-level in the pan.

8 represents the gate or valve proper for reversing the flow of the gas as required in

regenerative or gas-reversing furnaces. This gate is carried on wheels 9, running on tracks 10, which are preferably the lateral edges of the water-pan 2. The gate is entirely open below and has its lower edge normally below the water-level in the pan 2 and is otherwise wholly closed on the other five surfaces. It is connected to the wheels by means of arms 11, which extend beneath the bottom of the valve-casing 1. The gate or valve 8 is sufficiently long to cover the middle port 5 and one of the end ports 6 or 7 simultaneously when in its lowered or water-sealed position. The tracks 10 are each provided with the pairs of cams or elevations 12 and 13, up which the wheels 9 travel to lift the valve 8 out of the water, along which they travel to transfer the valve to another working position and down which they travel to lower the valve into the water seal. The valve 8 is provided with inwardly-projecting lugs 14 and 15, which coöperate with pairs of lugs 16 and 17 on the outer edges of the damper or gate 18, which is preferably a metal-flanged plate of a size to close the central port 5 when moved thereover. The gate 18 is supported on wheels 19, running on the tracks 20 in the pan 2. The pairs of lugs 16 are shown at the left-hand end of the gate 18 and the pair 17 at the right-hand end, the lugs 14 and 15 resting between the members of the respective pairs. It is clear that the lugs 15 could be omitted.

21 and 22 represent a pair of pistons for moving the valve 8.

23 represents a vertical plate secured to the bar connecting the wheels 9. It is provided with a vertical slot 24, in which rides the pin 25, secured to the piston-rod working in the cylinders 21 and 22. The slot 24 allows the wheels and valve 8 to move up and down without disconnecting the valve-moving means.

If the parts stand as shown on Fig. 2 and in full lines on Fig. 1, (the dotted line 23 representing the corresponding position of the valve 8,) the gas from the port 3 would pass into the valve-casing 1 and out therefrom through the port 7. After passing through the furnace (not shown) the spent gases go up through the port 6 into the hollow of the valve 8 and then down through the stack-port 5. When it is desired to reverse the

flow of gas in the furnace, the valve is moved to the right. It will be seen that for a time the wheels 6 travel on horizontal portions of the track. It is during this travel that the 5 lugs 14 and 15 move the valve 18 from its place between the ports 5 and 6, so as to cover the port 5. When the valve 18 is accurately over the port 5, the wheels 9 by running up the inclines of the elevated portions 10 12 and 13 carry the lugs 14 and 15 above and out of contact with the lugs 16 and 17. The valve 18 remains over the port 5 until the valve 8 has run nearly to the bottom of the inclines on the right-hand sides of the elevations 12 and 13, when the lugs 14 pass between the pairs of the lugs 17. The valve 8 moves to the right on horizontal portions of the tracks 10 till the valve 18 is moved from over the port 5 to a position between the ports 20 5 and 7, the valve 8 then occupying the position shown by the dotted lines 24. The dotted line 25 shows the position of the valve 8 when the wheels are about to ride to the right and upon the elevations 12 and 13. When 25 the valve 8 has been moved to its extreme right-hand position, the gas then passes from the port 3 down through the port 6, up through the port 7, and down the chimney-port 5. When the valve 8 is moved to the 30 left, the valve 18 is first moved over the port 5, when the interlocking lugs pass by each other, leaving the valve 18 there until the wheels 9 pass down from the inclines of the elevations 12 and 13. The lugs again interlock and the valve 18 is moved off to the left from the port 5.

Having described my invention, I claim—

1. In a water-sealed valve a casing having inlet and outlet ports, a main reversing-valve proper therein, normally covering said outlet, a second valve, and means for moving the latter to close the outlet before the main valve breaks the water seal and to open the outlet after the seal is again made.
2. In a water-sealed valve a casing having

inlet and outlet ports, a main reversing-valve proper therein, normally covering said outlet, a second valve, means controlled by the main valve for moving the second valve to close the outlet before the main valve breaks the water seal and to open the outlet after the seal is again made.

3. In a water-sealed valve a casing having inlet and outlet ports, a main reversing-valve proper therein, normally covering said outlet, a second valve within the main valve, and means for moving the latter to close the outlet before the main valve breaks the water seal and to open the outlet after the seal is again made.

4. In a water-sealed valve a casing having inlet and outlet ports, a main valve therein, normally covering said outlet, a second valve, interlocking connections between the main and second valves operative to move the second valve to close the outlet prior to the breaking of the water seal, inoperative while the main valve is out of the water, and again operative after the main valve is in the water to move the second valve from the said outlet.

5. In a water-sealed valve a casing having inlet and outlet ports, a main valve therein, normally covering said outlet, a second valve, a cam-track for said main valve to control its movements into and from the water, interlocking connections between the main and second valves operative to move the second valve to close the outlet prior to the breaking of the water seal, inoperative while the main valve is out of the water, and again operative after the main valve is in the water to move the second valve from the said outlet.

Signed at Pittsburg, Pennsylvania, this 8th day of December, 1905.

WILLIAM R. MILLER.
